ELECTRIC DEVICE FOR CUTTING GYPSO-PLASTIC DRESSINGS

Johann Niederhofer, Munich, Germany

Application August 10, 1932, Serial No. 628,199
In Germany December 12, 1931

6 Claims. (Cl. 128—317)

This invention relates to a device for cutting up gypso-plastic dressings. Circular saws have already been used for this purpose, but they present the inconvenience that with the same only straight cuts can be made. Devices are further known, which comprise a drill to be first bored perpendicularly into the gypso-plastic dressing and then pushed forward in the longitudinal direction of the dressing, exerting thus a cutting effect similar to a milling cutter. This method possesses the inconvenience that the threads of fabric, wadding or the like, situated in or under the dressing, wind around the revolving drill and cause stopping or breaking of the same.

According to the invention these inconveniences are obviated. The cutting tool is not revolving, but consists of a chisel-like tool driven in known manner by an eccentric gear and moving up and down, exerting a chisel-like effect parallel to the protecting holder for its foot and cuts open the dressing. This chisel-like tool is of peculiar shape which will be hereinafter described.

An embodiment of the cutting device according to the apparatus is illustrated by way of example in the accompanying drawing in which:—

Fig. 1 shows the same in longitudinal section,

Fig. 2 in front elevation, the casing cover removed.

Fig. 3 shows the chisel with foot in side elevation on enlarged scale.

Figure 4 is an elevational view of the chisel-like foot.

Figs. 4a, 4b and 4c show cross sections through the chisel-like tool on lines A—A, B—B and C—C of Fig. 4.

The driving mechanism for the cutting device consists of a generally known eccentric gear. In the form of construction illustrated a shaft 3 running in ball bearings 4 is journaled in a handle 1 and serves for driving the eccentric gear 5. This gear is accommodated in a casing 6 and consists of the eccentric proper 5 acting upon a roller 7 mounted in balls and rolling in an eccentric ring 8, which has above and below slidable pieces 9 and 10. The chisel 13 is inserted in the lower slidable piece 10. Guide bars 11 and 12 serve to facilitate the guiding of said slidable pieces 10. The eccentric gear is driven by a flexible shaft 15 coming from any suitable engine. A clutch 2 is provided between shaft 3 and the flexible shaft 15.

The characteristic feature of the invention is not the eccentric gear but the peculiar shape

of the cutting tool which is called chisel owing to its chisel-like action. This chisel 13 is composed of three portions of different thickness. The first portion 13a is short and saw-like so that it serves for ripping the gypso-plastic dressing. The next following portion in upward direction is a slightly longer but thinner saw-like piece 13b, the thickness of which corresponds to the width of the foot holder of the chisel. The third part 13c in upward direction is a drill-like piece, the edges of the drills being serrated for the purpose to eject the chips. This third part 13c of the chisel is thicker than the saw blade-like parts in order that the chips can be easily ejected, the cut being enlarged at the same time. This third part 13c is tapered from upwards to below and therefore takes up chips ejected by the saw-like parts 13a and 13b and conveys them towards the outer side. The chisel, in order to render it stable against the cutting pressure, has reinforcing ribs 14, a nose 14a of which bears against the slidable piece 10 (Figs. 1 and 2). The chisel 13 acts upon the foot 16 designed to be pushed under the dressing and terminating at the top end in an edge 16a, which continues along the foot holder 16b; whereas the cutting edge on the foot 16 serves to make incisions in the dressing from below, the cutting edges along the foot holder 16b serve for more easily guiding the foot in forward and backward direction. Also the rear side of the foot holder 16b has a cutting edge. The foot holder is fixed by a plate 17 standing at right angles (Figs. 1 and 2) on the casing 6. The foot 16 carries in its lower side an insulating plate 18, for instance of ivory.

The operation of the device is very simple. The foot is pushed under the gypso-plastic dressing and after the current has been switched on, the dressing is easily cut open by shifting of the apparatus, no pain being caused to the patient, and textile fibres and the like in or under the dressing forming no obstacle.

I claim:—

1. A cutting device for gypso-plastic dressings, comprising a chisel composed of three parts, the lowermost part being of a certain thickness and saw-like, the next higher part being also saw-like but thinner and longer than the lowermost part and the uppermost part being drill-like, the drill edges being serrated, the uppermost part tapering from above downwards.

2. Cutting device for gypso-plastic dressing comprising in combination a casing, an eccentric gear in said casing, a chisel projecting from said casing and adapted to be moved vertically up

and down by said eccentric gear, a foot for said cutter, a cutting edge extending along the upper end of said foot and from there along the foot holder, and a right angular plate connecting said foot holder with said casing of the eccentric gear.

3. Cutting device for gypso-plastic dressing comprising in combination a casing, an eccentric gear in said casing, a chisel projecting from said casing and adapted to be moved vertically up and down by said eccentric gear, a foot for said cutter, a cutting edge extending along the upper end of said foot and from there along the foot holder and also a cutting edge on the rear side of said foot holder, and a right angular plate connecting said foot holder with said casing of the eccentric gear.

4. Cutting device for gypso-plastic dressing comprising in combination, a casing, an eccentric gear in said casing, a chisel projecting from said casing and adapted to be moved vertically up and down by said eccentric gear, a foot for said cutter, a cutting edge extending along the upper end

of said foot and from there along the foot holder, a right angular plate connecting said foot holder with said casing of the eccentric gear, and an insulating foot plate, for instance of ivory, in said foot.

5. Cutting device for gypso-plastic dressings, comprising in combination a gear casing, an eccentric gear in said gear casing, a horizontal handle in which said gear casing is mounted, a roller of said eccentric gear, an eccentric ring surrounding said roller, and slideable elements running on rollers supported by said eccentric ring.

6. Cutting device for gypso-plastic dressings, comprising in combination a gear casing, an eccentric gear in said gear casing, a horizontal handle in which said gear casing is mounted, a roller of said eccentric gear, an eccentric ring surrounding said roller, slideable elements running on rollers supported by said eccentric ring, and guide bars for said slideable elements.
